UNITED STATES PATENT OFFICE.

HUGH E. FENCHELLE, OF GENOA, ITALY, ASSIGNOR TO WILLIAM L. KANN,
TRUSTEE, OF PITTSBURGH, PENNSYLVANIA.

INTERNAL-COMBUSTION ENGINE.

1,366,315.

Specification of Letters Patent. Patented Jan. 18, 1921.

Application filed June 18, 1918. Serial No. 240,613.

To all whom it may concern:

Be it known that I, HUGH E. FENCHELLE, a resident of Genoa, Italy, have invented a new and useful Improvement in Internal-
5 Combustion Engines, of which the following is a full, clear, and exact description, reference being had to the accompanying drawing, forming part of this specification, in which:

10 Figure 1 is a sectional view largely dia-
grammatic of an engine embodying my in-
vention;

15 Fig. 2 is a similar view of a portion of
the engine with the moving parts in different
positions.

20 My invention has relation to improve-
ments in internal combustion engines, and
more particularly to engines of the two-cycle
type in which the power is derived from the
25 combustion of the fuel mixture within the
engine cylinder.

Heretofore, numerous attempts have been
25 made to increase the power of engines of
this type by increasing the volume of air
introduced into the motor cylinder during
the compression stroke. In so far as I am
30 aware, such attempts have not been successful
to any great degree, because the supple-
mental air employed has been derived from
the same source of supply as that employed
35 for scavenging at the beginning of the com-
pression stroke. If it is attempted to in-
crease the pressure of this air, the results
are disadvantageous for two reasons: First,
40 the scavenging is then produced by means of
air under high pressure and high velocity
and imperfect scavenging results; and sec-
ond, the force absorbed by the pump which
45 supplies the scavenging air, largely if not
altogether offsets the increased power due to
the use of such air in the charge.

50 My invention is designed to increase the
power of engines of this character by the in-
troduction of high pressure air into the mo-
tor cylinder during the combustion stroke
and after combustion has been initiated. In
55 accordance with my invention, this supple-
mental air supply is derived from any suit-
able source, and its introduction into the cyl-
inder is controlled by means of an ordinary
valve actuated by suitable connections with
the movable part or parts of the engine.

In the accompanying drawing, I have
55 illustrated more or less conventionally a
form of engine embodying my invention.

In this drawing, the numeral 2 designates
the engine cylinder, 3 its piston, and 4 the
exhaust ports controlled by the piston. 5
designates a port for the introduction of
scavenging air, and 6 an auxiliary port for 60
the introduction of scavenging and charging
air. These ports are both controlled by the
piston 3, and except for structural reasons,
might be formed as a single port.

The air supply for the ports 5 and 6 is 65
from a source of air under relatively low
pressure, such as the pump 7 having the
piston 8. The numeral 9 designates an aux-
iliary air supply port which leads through a
valve seat 10 into a chamber 11, connected 70
by a passage 12 with a source of air under
relatively high pressure, such as the pump
13. The port 9 is controlled by a slide valve
14, mounted in the seat 10 and having a per-
ipheral port 15, adapted, when the valve is 75
in the right position, to form a means of
communication between the air chamber 11
and said port 9. This valve is shown as
actuated by a pitman rod 16, connected to a
crank 17 on a shaft 18, which may be geared 80
to the main crank shaft 19 in any known
manner, so as to rotate at the same speed as
said main shaft.

In Fig. 1, the parts are represented as in
the positions which they occupy at the time 85
the piston is at the end of the combustion
stroke, the exhaust port 4 having opened
as has also the scavenging port 5. As the
piston commences its compression stroke, air
under relatively low pressure continues to 90
enter the cylinder through the port 5 to con-
tinue the scavenging until such time as the
piston closes the exhaust ports 4. At this
time, the valve 14 has opened the port 6
and charge-forming air from the same 95
source of supply flows into the cylinder and
is compressed in the usual manner.

At the desired point in the compression
stroke, the port 9 is uncovered and the valve
14 is then in the position shown in Fig. 2, 100
thereby admitting air under high pressure
into the engine cylinder for the purpose of
effecting and supporting combustion there-
in. As the piston 3 passes the port 9, the
valve 14 will be closed before the exhaust 105
port 4 is again opened.

While I have shown the valve 15 as ar-
ranged when in the position shown in Fig.
1 to close the port 6, this is immaterial, as
55 ports 5 and 6 may both be controlled solely 110

by the piston 3. It will also be understood that any suitable form of valve may be employed to control the port 9, that the valve may be actuated by any suitable connection 5 with a moving part or parts of the engine, and that the source of air supply and the connections leading therefrom to the engine may be widely changed, without departing from the spirit and scope of my invention, 10 as set forth in the appended claims.

The advantages of my invention result from the provision of means whereby air under relatively high pressure may be forced into the engine cylinder during the 15 explosion stroke, after combustion has been initiated, thereby greatly increasing the power delivered by the engine.

I claim:

1. An internal combustion engine having 20 port means for introducing air during the compression stroke, means connecting said port to a source of air supply under relatively low pressure, the engine having another air-admission port connected with a 25 source of air supply under higher pressure, and a single valve controlling both said ports and operating to admit air to the engine cylinder through the main port on the compression stroke of the engine and to admit air at higher pressure through the second named port during a portion of the combustion stroke; substantially as described.

2. An internal combustion engine having 30 port means for introducing air during the compression stroke, means connecting said

port to a source of air supply under relatively low pressure, the engine having another air-admission port connected with a source of air supply under higher pressure, and a single valve controlling both said 40 ports and operating to admit air to the engine cylinder through the main port on the compression stroke of the engine and to admit air at higher pressure through the second named port during a portion of the 45 combustion stroke, the cylinder also having a scavenging port connected with the source of air which is under lower pressure; substantially as described.

3. An internal combustion engine having 50 port means for introducing air during the compression stroke, means connecting said port to a source of air supply under relatively low pressure, the engine having another air-admission port connected with a 55 source of air supply under higher pressure, and a single valve controlling both said ports and operating to admit air to the engine cylinder through the main port on the compression stroke of the engine and to admit air at higher pressure through the second named port during a portion of the combustion stroke, the cylinder also having a 60 scavenging port connected with the source of air which is under lower pressure, said 65 port also being controlled by the aforesaid valve; substantially as described.

In testimony whereof, I have hereunto set my hand.

HUGH E. FENCHELLE.
